(57) **CLAIM**

The ornamental design for a medical instrument set, as shown and described.

DESCRIPTION

FIG. 1 a perspective view of a medical instrument set, including a test insert and a cover, according to our new design;

FIG. 2 is a front view of a test insert of the medical instrument set;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a front, left perspective view thereof;

FIG. 9 is a front view of a cover of the medical instrument set;

FIG. 10 is a rear view thereof;

FIG. 11 is a left view thereof;

FIG. 12 is a right view thereof;

FIG. 13 is a top view thereof;

FIG. 14 is a bottom view thereof; and,

FIG. 15 is a front, left perspective view thereof.

The dot-dash broken lines depict the boundaries of the claim and form no part thereof.

The dotted lines depict portions of the medical instrument set that form no part of the claimed design.

1 Claim, 15 Drawing Sheets
